UNITED STATES PATENT OFFICE.

PATRICK M. WILLIAMS, OF NORTH WILKESBORO, NORTH CAROLINA, ASSIGNOR TO
MOORE DRY KILN COMPANY, OF JACKSONVILLE, FLORIDA, A CORPORATION OF
FLORIDA.

VENEER KILN.

Application filed November 20, 1920. Serial No. 425,473.

To all whom it may concern:

Be it known that PATRICK M. WILLIAMS, a citizen of the United States, residing at North Wilkesboro, in the county of Wilkes 5 and State of North Carolina, has invented certain new and useful Improvements in Veneer Kilns, of which the following is a specification.

This invention relates to an improvement 10 in veneer kilns and is of the general type of the invention set forth in my application Serial No. 383,530, and the fundamental object of this invention is to provide adjustable dampers for regulating the hot air passage 15 into the kiln.

In the accompanying drawings—

Figure 1 is a sectional view of a portion of a kiln.

Figure 2 is a view of a slightly modified 20 construction.

Figure 3 is a perspective view of the intake end of the kiln.

Figure 4 is a view showing the suction fans at the end of the kiln.

25 A represents the kiln shown in Figure 1. There are a series of heating coils 1, preferably five in number, with headers 2 and 3, at opposite ends and extending transversely thereof. The air inlet 4, is controlled by hinged doors 5, and the hot air passage or 30 throat 6, is regulated and controlled by two dampers 7 and 8 extending respectively from the roof and floor and one or both of which are connected thereto by hinges 9, whereby 35 either one or both may be adjusted to regulate the size of the throat 6, according to the amount of heat required in the kiln chamber and are adapted to direct the heat toward the bottom of the kiln.

40 In the modified form shown in Figure 2, the ventilating dampers are slightly different, the lower damper 11, being rigid and the upper damper 12, being hinged and adjustable.

45 In the upper damper 12, slots 13, are formed so that even when the adjustable

dampers are closed there is still a limited air passage through the throat.

In the construction shown in Figure 2 the headers 14 and 15, are both located at 50 the outer end and there are 6 coils of pipes. In both forms it will be observed that the air is heated on entering the kiln it being circulated by suction or pressure fans 16, shown in Figure 4. Both the intake and 55 outlet are controlled by adjustable doors or dampers so that the degree of heat of the air may be regulated to suit the requirements preparatory to passing through the kiln.

I claim—

1. A horizontal kiln having a heated chamber and a drying chamber, an upstanding damper and a swingingly adjustable dependent damper overhanging the latter forming an adjustable throat between the 60 two chambers.

2. A horizontal kiln including a heated chamber and a drying chamber and two overlapping dampers one being swingingly adjustable and forming an adjustable throat 70 between the two chambers.

3. A horizontal kiln having a heating chamber and a drying chamber, a throat between the chambers comprising an upstanding damper substantially perpendicular to the floor of the kiln, and a dependent damper of the kiln overhanging said upstanding damper at an angle thereto there being an opening between said dampers.

4. A horizontal kiln having a heating 80 chamber and a drying chamber, a throat between the chambers comprising an upstanding damper substantially perpendicular to the floor of the kiln, and a dependent damper of the kiln overhanging said upstanding 85 damper at an angle thereto there being an opening between said dampers, one of said dampers being swingingly adjustable relative to the other of said dampers.

In testimony whereof I affix my signature.

PATRICK M. WILLIAMS.
